DEEP WELL PUMPING MECHANISM

Robert T. Knapp, Pasadena, Calif., assignor of
one-fourth to Rudolph A. Reik and one-fourth
to Forrest O. Reik, both of Los Angeles, Calif.

Application January 10, 1939, Serial No. 250,143

11 Claims. (Cl. 103—245)

This invention relates to apparatus for pumping fluids. It is particularly adapted for use in pumping oil or other liquids from deep wells in which the liquid rises by natural hydrostatic pressure to relatively low levels. It relates to that type of pumping apparatus in which a compressed gas, such as air or the natural gas usually available in the oil fields, or other compressed fluid, is introduced into the lower portion of the well and utilized to force oil to the surface of the well by displacement from a fluid-tight pumping chamber which is intermittently filled with oil from the well.

The pumping cycle in pumps of this type consists of two periods or phases. During one phase the pumping chamber is being filled with oil from the well at a rate of flow determined largely by the standing level of the oil in the well and the rate of inflow of the oil from the oil-bearing strata. During the second phase the oil is being forced into the delivery conduit from the pumping chamber at a rate dependent upon the pressure of the pumping fluid.

One of the objects of this invention is to provide a control mechanism capable of adjustment to initiate the action of each phase immediately upon the termination of the action of the preceding phase.

Another object of the invention is to provide an apparatus and a method of operating it, which will accommodate valves of relatively large effective flow capacity.

Another object is to provide valves which will operate promptly and rapidly.

Another object is to provide mechanism which will operate the valves controlling the application of the pumping fluid to the pumped liquid in a positive manner and independently of any influence by the level of the oil in the well, or by the changing pressure conditions of the liquid incident to the pumping cycle.

Another object is to provide a fully chronometric control of the pumping cycle which will be independent of any reactive influence by the conditions incident to the pumping cycle.

Another object is to provide such a chronometric control which will be adjustable so as to vary the duration of the complete cycle of pumping operations, or to vary the relative duration of the two phases of the cycle.

Another object is to actuate the mechanism effecting this type of independent chronometric control by a fluid under pressure, preferably obtained from the same source as that from which the displacement pumping fluid is obtained.

In order to first apply fluid pressure to the liquid in the pumping chamber and subsequently remove the fluid pressure in the most rapid possible alternation, it is essential that two entirely separated conduits for the pumping fluid be provided: one, a supply conduit for conducting it under pressure to the pumping chamber, and a second or "bleeder" conduit for relieving the pressure of the pumping fluid in the pumping chamber during that phase of the pumping cycle in which the pumping chamber is being filled with a charge of liquid. It is further essential that the supply conduit be filled at all times with fluid under full pressure for the full length of the well so that compressed fluid may be instantly available for application to the pumping chamber immediately upon the filling of the pumping chamber with liquid. This is best accomplished by providing each conduit with its own valve. Accordingly, in this invention separate inlet and outlet valves for applying and removing fluid pressure from the liquid in the pumping chamber are located adjacent the pumping chamber and are operated in an entirely chronometric fashion. This is made feasible by locating the chronometric mechanism adjacent the pumping chamber, which is in turn made a practical possibility by using a chronometric mechanism adapted to be motivated by the same compressed fluid as that which is used to force the oil to the surface of the well.

It is, therefore, a further object of my invention to provide a fully chronometric valve control mechanism adjacent the pumping chamber which will operate two rapidly and simultaneously acting valves controlling respectively the inflow and outflow of pumping fluid in separate conduits each of which extends to the pumping chamber.

It is a further object of my invention to provide a positively operated liquid intake valve controlling the flow of liquid from the well into the pumping chamber which will preferably be chronometrically operated in timed relationship with the chronometric operation of the two valves controlling the inflow and outflow of pumping fluid to and from the pumping chamber. These liquid intake valves in pumping apparatus of standard construction are check valves which are opened and closed by the changing pressures of the liquid in the well upon the upper and lower surfaces of the valve. The operation of such check valves is characterized by a lag which shortens the effective period of liquid inflow from the well and the effective period of expulsion of

the liquid from the pumping chamber to the surface of the well, thereby decreasing the quantity of oil delivered during each pumping cycle. Also the resistance of the flow of the liquid during the period of the slow opening movement of check valves of this type causes evolution of gas, if the liquid is petroleum. The evolution of gas decreases the amount of liquid inflow, and otherwise interferes with the effective operation of the pump. Furthermore, when or if the pressure difference falls below that required to operate such check valves, the capacity of the pump is decreased and the operative cycle may be prematurely terminated. In my invention, the liquid inflow valve is preferably opened and closed positively by power-operated means and in timed relationship with the operation of the pumping-fluid valves so that the inflow of liquid from the well into the pumping chamber and the outflow of spent pumping fluid therefrom may be terminated, and the inflow of compressed pumping fluid into the pumping chamber may be initiated, rapidly and simultaneously, and at the termination of the pumping phase of the cycle the first two flows may be initiated and the latter flow terminated rapidly and simultaneously.

Other objects of this invention are to provide a petroleum displacement pump, in which arrangement of the pumping chamber and valves therefor is such as to permit a rapid filling of the chamber without the evolution of gas as the oil moves into the chamber; to provide an operating mechanism which will continue to function even though normal movements of the pumping mechanism may be at times prevented due to interference of gravel, valve failure, or other cause; to provide a chronometric control mechanism which is proof against contamination and which will not stop on dead center; to provide a pumping mechanism which is well adapted for operation with other similar units with as many stages as may be necessary to produce the desired lift with the pressure of pumping fluid available, which can be installed within well casings of small diameter, and will handle liquids containing sand or other abrasive material.

It is another object of my invention to provide a structural arrangement of parts adapted to accomplish the objects above set forth which will be inexpensive, compact, readily assembled, sturdy, and of such a character as to require a minimum of attention, repair, adjustment, and replacement of parts.

Other objects will be apparent from a reading of the following description and drawings.

In the drawings:

Fig. 1 is a view in vertical longitudinal section and elevation of a well and a pumping apparatus embodying my invention.

Fig. 2 is a diagrammatic vertical sectional view of the lower portion of the well and apparatus.

Figs. 3 and 4 are vertical sectional views of two contiguous portions of the lower end of the pumping apparatus.

Fig. 5 is a central longitudinal vertical section of the control mechanism.

Fig. 6 is a vertical sectional view of that portion of the pumping apparatus shown in the upper end of Fig. 3, taken along the line 6-6 70 of Fig. 3.

Fig. 7 is a horizontal sectional view taken along the line 7-7 of Fig. 4.

Fig. 8 is a fragmentary, central longitudinal vertical sectional view of the control mechanism

shown with an additional pipe connection for operating a second pumping mechanism.

Referring to Fig. 1, a well casing 11 extends from a ground level 12 to an underground strata 13 containing the oil or other liquid which it is desired to pump to the surface of the well. This casing is provided with the usual perforations 14 for admitting the oil from the strata into the casing in which it rises by hydrostatic pressure and stands at a level 15. Within this casing is installed and appropriately suspended an oil delivery pipe or conduit 16 and an outer concentrically assembled compressed gas pipe 17 spaced from the oil pipe 16 to provide a chamber of annular cross section for the passage of compressed gas from the ground level to the pumping mechanism in the well, where it is utilized to actuate the pumping mechanism. The oil flowing upwardly in the pipe 16 is led off to any desired delivery or storage destination through a discharge pipe 18, and compressed gas is supplied to the pipe 17 from a suitable source such as a compressor 19 through a pipe 20. A pumping apparatus 21 is secured to and supported by the lower ends of pipes 16 and 17 in a manner to be presently described, and secured to this pumping apparatus and supported thereupon is a tubing 22 which extends upwardly to a point above the standing level 15 of the oil in the well and is concentrically spaced around the pipe 17. It acts as a vent or "bleeder" pipe for the spent compressed gas after it has performed its work of operating the pumping apparatus.

An explanation of the diagrammatic showing of the pumping apparatus in Fig. 2 will facilitate an understanding of its structure as shown in Figs. 3 to 7. The three conduits and tubing 16, 17, and 22, which are actually concentrically related, are for diagrammatic simplicity shown in vertical parallel relationship in Fig. 2. The showing of the pumping apparatus 21 is also diagrammatic in character. A pumping chamber 23 communicates with the oil in the well through a port 24; with the oil discharge, delivery, or lift pipe 16 through a port 25; with the pipe 17 through a port 26; and with the vent tubing 22 through a port 27. The port 24 is provided with an inwardly and upwardly opening valve 28 which is preferably power operated and is so shown and described herein. The port 25 is provided with an upwardly opening check valve 29 which opens when the pressure of the oil in the pumping chamber exceeds the pressure of the column of oil standing in the discharge pipe 16, and closes when the pressure in the pumping chamber falls below that of the discharge pipe. Valves 30 and 31 in the intake and outlet ports 26 and 27 respectively are mechanically connected and power operated by compressed gas intermittently delivered to them by a control mechanism 32 which also controls the intermittent delivery of operating gas to the power operated valve 28. This control mechanism is constructed and arranged, as will be presently explained, to, at one instant, simultaneously open the valves 28 and 31 and close the valve 30, and, at the instant of termination of a predetermined time interval thereafter, simultaneously close the valves 28 and 31 and open the valve 30.

Provision may be made for the delivery of compressed gas from the gas pipe 17 to the oil delivery pipe 16 through a passage 33 controlled by an adjustable valve 34. This valve may be adjusted from the ground level to vary the effec-

tive orifice through which the gas may pass from the pipe 17 to the pipe 16. Gas injected into the oil column in this manner is mixed with the oil, lightening the weight of the column of oil in the pipe 16, and facilitating the work of the pumping apparatus in the manner of the standard gas lift pumps.

The control mechanism 32 is operated by compressed gas which it receives from the pipe 17. It is constructed to intermittently interrupt the flow of gas therein. After leaving the control mechanism, the compressed gas is conducted to the three power-operated valves 28, 30, and 31, each of which is operated in one direction by the application of the gas pressure and is automatically operated in the other direction upon release of the gas pressure when the flow of gas is stopped by the control mechanism 32. The control mechanism is practically unaffected by well conditions, being actuated and controlled solely by the effective pressure of the gas in the pipe 17. This effective pressure is the difference between the pressures on the high and low pressure sides of the control mechanism, which pressures are both substantially constant. The pressure on the high pressure side is compressor 19 and is practically unaffected at the lower end of the pipe 17 by the level of the oil in the well, or the level or pressure of the coil in the pumping chamber, or by any mechanical or other changes effected in the course of the operation of the pumping mechanism.

In explanation of why the pressure at the lower end of the pipe 17 is thus unaffected, we shall assume that the compressor develops a pressure of 500 pounds, which is a standard pressure for gas-operated, deep well, displacement pumps, that the well is 4,000 feet deep, and that the pipe 17 is a $2\frac{1}{2}$ " O. D. pipe. A simple scale computation, based on the drawings, will show that the available reservoir volume of the gas chamber in the pipe 17 bears a ratio to the available reservoir volume of the empty displacement chamber 23 of 340 to 1. Bearing in mind that the take-off pipe to the control mechanism 32 is teed, as will later appear, into the take-off pipe from the pipe 17 to the displacement chamber 23, at a point closely adjacent the lower end of the pipe 17, and also bearing in mind that the skin friction in the pipe 17 is negligible and that the take-off pipe to the chamber 23 and its orifice into that chamber, as may be seen in Fig. 4, are small, and consequently the rate of flow therethrough into the displacement chamber 23 is low, it is demonstrable by formulae expressing the laws governing pneumatic pressures and velocities that the drop in pressure at the T connection to the control mechanism 32 due to the opening of the valve 30 is substantially less than 5% of the pressure at the compressor, or substantially less than 25 pounds. This drop in pressure is for all practical purposes negligible in comparison to the impressed maximum pressure of 500 pounds and has no appreciable effect upon the functional operation of the control mechanism 32. If the oil inlet or oil outlet valves of the displacement chamber operate defectively or fail completely, or if the well goes dry of oil, these events will not affect to any appreciable degree the fluid pressure available to and impressed upon the control mechanism 32.

The spent gas which has been used to operate the valves 28, 30, and 31 and the control mechanism 32 is conducted to a gas chamber 87

5 between the casing 11 and pipe 17, extending from the top of the oil column 15 to a casing head 11a. A pipe 87a is provided to conduct the gas from the chamber 87 to the compressor 19 or other delivery point. The pressure of the gas within the chamber 87 is but slightly above atmospheric pressure, and under some conditions may even be below atmospheric pressure due to the suction exerted upon it by the compressor when the gas is led from the chamber 87 to the compressor. In any event, the gas pressure within the chamber 87 is very low compared with that within the pipe 17, and while the pressure of the chamber 87 varies slightly with the fluctuation of the oil level 15, it is substantially constant during the operation of the pumping apparatus. The effective gas pressure available for operating the several valves and control mechanism of the pumping apparatus in a manner to be presently explained is either the difference between the pressure in the pipe 17 and that in the chamber 87, or is the difference between the pressure in the pipe 17 and atmospheric pressure. It is apparent, therefore, that in either case it is substantially and practically independent of any changes in the level 15 of the column of oil in the well.

Immediately upon the opening of the valves 28 and 31 and the closing of the valve 30, oil flows freely into the pumping chamber under the hydrostatic action of the oil in the well casing and in the oil-bearing strata and rises in the pumping chamber. At a moment preferably just as the rising oil contacts the ports 26 and 27 and their 35 associated valves 30 and 31, the control mechanism, which has been previously adjusted to operate on a time cycle determined by the conditions of the installation, closes the valves 28 and 31 and opens the valve 30. Compressed gas is 40 then admitted to the pumping chamber, and the charge of oil or mixed oil and gas therein lifts the valve 29 and is forced through the delivery pipe 16 to the surface of the well and out through the discharge pipe 18. After the pumping chamber is emptied by the action of the compressed gas, the control mechanism again operates to open the valves 28 and 31 and close the valve 30, whereupon the process of recharging the pumping chamber and delivery pipe is repeated. The valve 29 at the end of each expulsion of oil from the pumping chamber closes under the gravity action of the oil remaining in the delivery pipe 16, thereby preventing any back flow of oil and conserving the entire volumetric capacity of 55 the pumping chamber 23 for the new charge of oil from the well.

Figs. 3 to 7 show the actual mechanical construction and arrangement of the pumping apparatus and its several parts to effect the cycle of operations described in connection with the above explanation of the diagrammatic Fig. 2. The lower ends of the pipes 16 and 17 are threaded or otherwise secured to an adapter 35. The adapter has a central bore 36 communicating with the interior of the pipe 16. The lower end of the adapter is formed to provide a Y-branched pipe connection 37 into which are threaded or otherwise secured two oil delivery pipes 38. These pipes extend downwardly to a valve block 39 into which they are threaded or otherwise secured in communication with vertical bores 40 and 41 thereof and which they support in vertical position in the well. The upper end of this block 39 is externally threaded at 42 to receive the lower end of the vent tubing 22 which is sup-

ported by the block and extends upwardly to a point above the standing level of the oil in the well.

Into the lower ends of the bores 40 and 41 are threaded or otherwise secured oil delivery pipe sections 38a which are joined by means of a Y-branched connection 43 to a single oil delivery pipe section 44. This latter pipe section is coupled at its lower end to a check valve housing 45 formed with a valve seat 46 and contains the usual check valve ball 29a associated with the seat and limited in its upward movement by stops 47 suitably mounted in the housing 45. To the lower end of the housing 45 is coupled a strainer cylinder 48 provided with the usual perforations 48a to permit passage of the oil and exclude gravel and other foreign bodies. A frame element 49 of the oil intake valve 28 is threaded into a tapped hole 51 in the lower end of the strainer cylinder and is supported thereby. The valve 28 is made in two bell-shaped parts 52a and 52b, threaded together at 53. An interior chamber 54 of the valve encloses an enlarged lower end 58 of the valve frame element 49 and is operatively connected thereto by tension springs 55 each of which is secured at its upper end to the frame element 49 and at its lower end to the valve wall. The upper part 52a of the valve is formed with a circular flange 56 positioned between a depending skirt 57 of the strainer section 48 and the frame element 49, a construction which serves to prevent heavier foreign bodies finding their way into the interior of the valve chamber 54.

The lower end of the valve frame element 49 is drilled to provide a downwardly opening cylindrical recess 59 which constitutes a piston chamber in which reciprocates a piston 60. A plunger pin 61 is integrally connected to the lower end of the piston 60 and is formed with a rounded end at its lower extremity which fits within a conforming internal recess 62 in the lower end of the wall of the valve part 52b.

An axial bore 10 of relatively small diameter in the frame element 49, communicating with a compressed gas conduit 11 at its upper end, serves to conduct compressed gas to the piston chamber 59. The piston 60, when gas is admitted to the piston chamber, forces the valve 28 downwardly against the action of the tension springs 55 which hold the valve in contact with the plunger pin 61 at all times, and retrieve the valve to its uppermost position when the pressure of the gas upon the piston is removed. The mating surfaces of the end of the pin 63 and the recess 62 are designed to permit a small rocking action of the valve about the end of the pin which is limited by the lateral play of the flange 56 between the frame element 49 and the skirt 57. This rocking action allows for misalignment of the valve on its seat and facilitates the dislodging of dirt which may be caught between the valve and its seat.

The extreme lower end of the valve is provided with a projecting tip 64 which splits into an annular stream the upwardly flowing oil in the port 24. Above this tip 64 the valve is formed with an annular, upwardly and outwardly sloping surface 65 which engages a replaceable valve seat 66 seated in a coupling 67. This coupling is secured at its upper end to a section of tubing 68 which is in turn externally threaded upon the lower end of the valve block 39. The tubing 68 is the means of support of the coupling 67 and defines between the valve block 39 and the coupling 67 the pumping chamber 23 in which are housed the oil delivery pipe 44 and intake valve 28.

with their associated parts described above. This chamber also houses mechanism for operating the valves controlling the inflow and discharge of pumping fluid, as will be later described. A spider **68a** secured between the tubing **68** and the strainer cylinder **48** serves to position the valve mechanism **28** coaxially with respect to the valve seat **66**.

A strainer section 72 is threaded upon and supported by the coupling 67, and oil entering the production string through this strainer flows upwardly through the port 24 in the coupling 67, and thence into the pumping chamber 23 by way of a streamlined annular passage 73 between the valve surface 65 and the valve seat 66. When compressed gas or other pumping fluid is introduced into the pumping chamber 23, and the valves 28 and 31 are closed, the oil will be forced out of the pumping chamber through the perforations 48a and the port 25, and after lifting the valve ball 29a it will be conducted to the surface of the well through the pipe section 44, Y branch 43, pipe sections 38a, bores 40 and 41, pipe sections 38, Y branch 37, bore 36, and delivery pipe 16.

Compressed gas or other pumping fluid under pressure is conducted from the compressor 19 or other source through the pipe 17 to the adapter 35. The adapter is made with an annular chamber 74 which communicates with the interior of the lower end of the pipe 17. This chamber 74 is connected by a port 75 to a gas pipe 76 which is secured to and supported by the adapter 35 at its upper end and extends downwardly to the valve block 39 by which it is supported at its lower end by means of a threaded connection therewith in communication with a vertical bore 77 in the block. This bore extends through the block to the pumping chamber 23 and constitutes an inlet port for the compressed gas. The flow of gas through this port is controlled by the upwardly opening valve 30 which engages a valve seat 78 screwed into an enlarged lower end 79 of the port. The gas pipe 76, bore 77, and aperture of the valve seat 78 are small relative to the cross-sectional area of the gas chamber in the pipe 17, and the rate of flow therethrough is correspondingly retarded, even should the chamber 23 and pipe 16 be entirely empty and at atmospheric pressure. A valve stem 30a which is an integral extension of the valve 30 is slidably mounted in the valve seat 78 and contacts at its lower end and rests upon a horizontal lever 80 which is pivoted at 81 to an extension 82 of the valve block 39. Since the upper face of the valve 30 is subjected to gas pressure at all times, the valve will remain closed except when it is moved upwardly by the mechanical action of the lever 80. When the valve 30 is lifted by this lever, compressed gas flows into the pumping chamber. If at this same time the oil intake valve 28 is closed and there is no outlet in the upper part of the pumping chamber for the compressed gas, any oil standing in the pumping chamber is forced into the delivery pipe 16.

An annular chamber 83 between the tubing 22 and the gas pipe 17 is open at the upper end of the tubing 22 to the gas space 87 above the level 15 within the well casing 11. This annular chamber is in communication with a chamber 84 between the adapter 35 and the valve block 39 by means of an annular passage 85 between the adapter 35 and the tubing 22. The adapter is supported laterally within the casing 22 by

adapter lugs 86 positioned within this passage 85. Fluid discharged into the chamber 84 will then find its way upwardly through the passage 85 and the chamber 83 to the gas space 87. The compressed gas admitted through the valve 30 to the pumping chamber is exhausted into the chamber 84 and thence into the gas space 87 by way of the port 27 in the lower wall of the valve block 39 and a bore 88 which is an enlarged extension of the port 27 and extends to the upper horizontal wall of the valve block 39.

The flow of gas through this port and bore is controlled by the downwardly opening valve 31 which coats with a valve seat 90 at the lower end of the port 27 to prevent the escape of gas from the pumping chamber 23. A coiled spring 91 is seated in the bore 88 between a stationary ring 92 and the upper end of a valve arm 93 and acts to press the valve away from its seat. The lower end of the valve 31 is a piston 94 which reciprocates in a piston chamber 95 of a cylinder block 96 rigidly secured to the lower end of the valve block 39. The outer end of the lever 80 is disposed in a transverse slot 97 in the upper portion of the piston 94 and is provided with a bearing 98 adapted to have sliding engagement with adjacent surfaces of the slot 97, whereby the motion of reciprocation of the piston imparts an oscillatory movement to the lever 80, which in turn alternately raises and permits the lowering of the valve 30.

The piston 94 is forced upwardly against the action of the compression spring 91 when compressed gas is admitted to the piston chamber 95 through an axial bore 99 in the lower end of the cylinder block 96 from a gas pipe or conduit 100. This conduit 100 branches from the conduit 71 which has already been described as a supply conduit for the piston chamber 59 of the oil intake valve 28. The conduit 71 receives its supply of compressed gas from the supply conduit 76 through a series of fluid conductors, beginning with pipe 101 which is connected to the conduit 76 at 102 preferably closely adjacent the upper end of the pipe 76, and continuing 45 with a gas filter 103, a pipe 104, the valve engine 32, a pipe 106, and a bore 107 in the valve block 39. The pipe 106 is threadedly or otherwise secured in the upper end of a bore 107, and the pipe 71 is threadedly or otherwise secured in the lower end of the bore 107.

The valve engine or control mechanism 32 is actuated solely by the energy of the compressed gas delivered to it through the pipe 104, and it performs the function of alternately supplying 55 gas to and venting it from the pipe 106 and the valve operating cylinders connected thereto. Considering the succession of events from one gas-flow shut-off to the next gas-flow shut-off as one pumping cycle, that phase of the cycle 60 which begins with the shut-off and ends with the reestablishment of the flow as the charging phase, and the remainder of the cycle as the pumping phase, the valve engine is so constructed and designed that it can be adjusted to increase or decrease within desired limits, depending upon conditions, the time interval occupied by each phase independently of the other phase. The engine exercises a chronometric control of the valves 28, 30, and 31, causing them to operate on a predetermined time cycle, the length of which is entirely independent of well conditions, hydrostatic or velocity head of the oil in the well, accidental sticking of one or more of the 75

valves, viscosity or other qualities of the oil, depth of the well, variations in the head pumped against, or any variable factors whatever other than the effective pressure of the gas in the supply pipe 104 and the adjustment set within the engine, which two factors alone determine the length of the cycle. As has been heretofore explained, the effective pressure in the pipe 104 is, for any given pressure at the compressor, substantially constant. Similarly, the length of each of the two phases of the cycle in absolute time is dependent solely on the effective gas pressure and the adjustment set, and the length of each phase relative to the other phase is dependent solely upon the adjustment set. During the charging phase in which the engine prevents the flow of compressed gas to the piston chambers 59 and 95, the valve 28 is held open by tension springs 55, the valve 31 is held open by the compression spring 91, and the valve 30 is held shut by pressure of gas on its upper surface, in the absence of any mechanical lifting pressure exerted upon the valve stem 30a by the lever 80, this lever occupying its lowermost position by virtue of its connection with the piston 94. With the valves in this position, oil will flow into the pumping chamber 23. At the end of the time interval for which the engine 32 is set, which preferably is when the oil level in the pumping chamber reaches the ports 26 and 27 and their associated valves 30 and 31, compressed gas is given a free path through the conduit 106 to the piston chambers 59 and 95, the three valves are reversed in position, and oil is forced by pneumatic pressure from the pumping chamber to the delivery pipe of the well. At the end of a second time interval for which the engine is also set, which is preferably when the gas reaches the port 25 and the valve 29, the flow of compressed gas is again shut off, the delivery flow ceases, and the charging of the pumping chamber is repeated. It is apparent that by knowing the position of the liquid level 15 with relation to the valve 28, together with the effective viscosity of the liquid, the optimum length of time for both the charging and discharging operations can be calculated and preset on the engine 32. The charging phase can be adjusted to exactly the length of time required to fill the pumping chamber under the actual conditions of an installation. The pumping, lifting, or discharging phase can be adjusted to exactly the length of time required to deliver the charge into the delivery pipe under the given conditions of available gas pressure, well depth, and characteristics of the pumping apparatus. By such a calculated adjustment the pump can be caused to deliver oil at a maximum rate of flow.

The engine frame consists of an upper cylindrical block 108, a central cylindrical block 109, a lower cylindrical block 110, an upper section of tubing 111 threaded to and connecting the blocks 108 and 109, and a lower section of tubing 112 threaded to and connecting the blocks 109 and 110. These sections define, between the blocks which they connect, an upper chamber 113 and a lower chamber 114.

The engine supply conduit 104 is secured to the central block 109 in communication with a radial port 115, and the conduit 106 for conveying gas from the engine to the valves of the pumping apparatus is secured to the central block in communication with a radial port 116. These ports 115 and 116 communicate at points near the longitudinal center of the block 109 with an

axially disposed longitudinal bore 117 which extends from end to end of the central block 109. A port 118 of L-shaped configuration communicates with the axial bore 117 at 120 and leads therefrom to the chamber 114. A port 119 connects the port 116 with the chamber 113. Two radially disposed exhaust ports 121 and 122 connect the axial bore 117 with the chamber 84 in which the valve engine 32 is mounted. Two ball cages 123 and 124 are suitably mounted in cylindrical recesses in the upper and lower walls, respectively, of the central block 109 in axial alignment with the bore 117, and house respectively two valve balls 125 and 126 which have coacting relationship with two valve seats 127 and 128 respectively formed at the opposite ends of the bore 117. These valve balls control the passage of gas from the chambers 113 and 114 to the exhaust ports 121 and 122, which, when the corresponding valve ball is in the open position, takes place through a plurality of parallel, longitudinally arranged ports 129 and 130 in the cages 123 and 124 respectively, then through disc-shaped chambers 131 and 132 respectively defined between the cages and the inner walls of the recesses in which the cages are mounted, and thence by the valve seats 127 and 128 to the exhaust ports 121 and 122. The chambers 131 and 132 and ports 129 and 130 also serve to connect the ports 119 and 118 with the chambers 113 and 114 respectively at all times.

A piston slide valve 133 is mounted in the bore 117 and consists of two piston portions 134 and 135 which snugly fit the bore, a central cut-away portion 136, and two reduced end portions or pins 137 and 138 adapted to engage and dislodge from their seats the valve balls 125 and 126. This over-all length of this piston valve is such that when one valve ball is seated, the other is held near the outer portion of its cage. The disposition of the piston portions 134 and 135 and the intermediate cut-away portion 136 is such that when the ball 126 is seated, gas can pass from the port 115 to the port 118, and when the ball 125 is seated, gas can pass from the port 115 to the port 116.

The upper block 108 has a downwardly extending hollow cylindrical boss 139 in which is slidably mounted a plunger 140. A bellows 141 of fluid-proof material is mounted concentrically about the boss 139, being secured in fluid-tight manner between an annular flange 142 of the plunger 140 and the lower wall of the block 108. Small ports 143 in the base of the boss 139 connect the interior with the interior of the bellows 141. A coiled compression spring 144 seated in a cylindrical recess in the lower end of the plunger 140 presses downwardly upon a disc 145 which is limited in its downward movement by a recess cap 146. Rigidly secured to the disc 145 is a pin 147 slidably mounted in the cap 146 and which is adapted to engage the ball 125 and impart thereto a movement longitudinally of the engine.

At the other end of the engine the block 110 is formed with an upwardly extending, axial, cylindrical projection 148 which fits within and has slidable engagement with a cylindrical recess 152 in the lower end of a plunger 149. A bellows 150 similar to the bellows 141 is secured between an annular flange 151 on the plunger 149 and the upper wall of the block 110. Radial ports 153 connect an axial bore 154 in the projection 148 and in the block 110 with the interior of the bellows 150.

A compression spring 155 is mounted in an axially disposed cylindrical recess in the upper end of the plunger 149 and presses upwardly against a disc 156. A pin 157 rigidly secured to this disc 156 slides within a recess cap 158 which limits the upward movement of the disc and pin. The pin is adapted to engage the ball 126 and impart a movement thereto longitudinally of the engine. A coiled compression spring 159, which is seated between a ring 160 threaded on the plunger 149 and a ring 161 slidably fitted within the tubular section 112 and held against movement therein by an inwardly projecting annular flange 161a thereof, acts to urge the plunger upwardly at all times. Ports 162 serve to provide fluid communication between the portions of the chamber 114 above and below the ring 161. A conduit pipe 163 connects the bore 154 in the lower block with a similar axially disposed bore 164 in the upper block which extends from the upper end of the block 108 to the interior of the boss 139. A slightly tapered constricted section 165 of this bore 164 affords a seat for a needle valve 166. This needle valve is free to reciprocate within the bore section 165. Its reciprocatory movement is limited in one direction by engagement of its head 166a with the lower end of a hollow cylinder 167, the lower portion of which is longitudinally split at 167a, and the upper end of which has threaded engagement with an upper enlarged portion 168 of the bore 164. The cylinder can thus be longitudinally adjusted upon its threads within the bore portion 168. Its movement in the other direction is similarly limited by the lower end of a pin 169a integrally formed with an adjustable stop nut 169 which is threadedly mounted within the cylinder 167. A light coiled spring 168a interposed between the nut 169 and the needle valve head 166a applies a slight downward pressure to the needle valve at all times. A threaded plug 170 closes the upper end of the bore 168, and upon its removal a suitable tool can be inserted within the bore for manipulating the adjusting cylinder 167 and the adjusting nut 169.

The engine operates in the following manner. The conduit 163, bores 154 and 164, the interior of the boss 139, the recess 152, and the interior of the two bellows are filled with oil of a type suitable for hydraulic work. The spring 159 holds the piston valve 133 in its uppermost position when the engine is idle, and operation of the engine begins with the valve in this position. The spring prevents the valve 133 standing in a midway dead center position. When compressed gas is supplied through the conduit 104, it finds its way through the ports 115 and 118 to the chamber 114 in which it builds up pneumatic pressure sufficient to urge downwardly the plunger 149 against the spring 159. The bellows 150 is shortened, and the oil within it and within the recess 152 is moved through the bore 154 and the conduit 163 to the bore 164. Here it flows downwardly through the constricted passage 165. The needle 166 is at this juncture at its lowermost position with its head 166a resting upon the lower end of the adjustable cylinder 167, where it is held by the spring 168a. In this position the needle does not quite fill the passage 165, and oil can slowly flow into the interior of the boss 139 and the bellows 141. The plunger 140 moves slowly downward, and after a definite time interval, which is obviously determined by the position in which the needle 166 is held by the lower end of the adjustable

cylinder 167, the pin 147 contacts the ball 125, which at first resists the pressure exerted upon it by the pin because of upwardly acting gas pressure upon the ball 126. As a result, the spring 144 is compressed. When a tip 146a of the cap 146 comes in contact with the ball 125, the seating of the ball 126 is broken, and then the spring 144, through the pin 147, causes the piston valve 133 to snap to its lower position, in which the ball 125 is seated. This spring 144 and the corresponding spring 155 prevent the valve 133 stopping during its reciprocations at a midway dead center position. Until the piston valve is snapped from its upper to its lower position, the gas in the chamber 113 and in the conduit 106 is free to flow through the ports 129 and 119, respectively, to the chamber 131, the bore 117, and the exhaust port 121, and thence to the gas space 87.

After the piston valve has been snapped to its lower position, the escape of gas in the chamber 113 is cut off at the valve seat 127. The piston section 134 closes the port 118, and the section 135 uncovers the port 116, allowing gas to flow from the conduit 104 to the conduit 106 through which it is conducted to the three valves of the pumping apparatus, as has been heretofore described, where the charge of oil in the pumping chamber is then pumped to the delivery pipe. The port 119, which communicates with the port 116, conducts gas to the chamber 113, compressing the bellows 141 and reversing the movement of the oil through the pipe 163. The needle 166 is moved upwardly by hydraulic friction with and the pressure differential of the oil until its head contacts the pin 169a of the adjustable stop nut 169, which obviously permits the engine oil to flow to the lower end of the engine more rapidly than it flowed to the upper end of the engine. Since it usually takes less time to discharge the charge of well oil from the pumping chamber to the delivery pipe by the pneumatic action of high pressure gas than it does to bleed and recharge the pumping chamber under the hydrostatic action of the oil in the well, it is desirable that the pumping phase of the cycle be of shorter duration than the charging phase. When the engine oil flows back to the lower end of the engine and to the interior of the bellows 150, the plunger 149 is raised, eventually snapping the piston valve 133 to its upper position, whereupon the cycle is repeated.

If desired, provision may be made for jetting compressed gas into the column of oil in the delivery pipe 16 to decrease the weight of the column and thereby decrease the load on the pumping apparatus in the well known manner of gas lift pumps. In Fig. 3 is shown means for incorporating such a gas lift with a pumping apparatus constructed in accordance with this invention. Referring to the upper end of Fig. 3, a tapered slot 33 in the pipe 16 which is wider at its lower end permits gas to flow from the annular chamber between the pipes 16 and 17 into the column of oil in the pipe 16. By rotating the pipe 16 at the ground level it will turn on its threads within the adapter 35 and be raised or lowered to shorten or lengthen the effective portion of the slot 33 above the upper end of a packing nut 171 threaded on a flange 172 on the adapter. If desired, the cycle can be so regulated, by regulation of the adjustable cylinder 167 and the adjustable stop nut 169, that at the end of the discharge phase the valves will not be reversed until some gas has passed through the

valve 29, which, commingling with the oil in the discharge pipe 16, will assist in effecting the gas-lift action.

Where the diameter of the well permits, the mechanism shown in Fig. 4 may be duplicated at the bottom of the well to afford a duplex acting pump to provide a continuous rather than an intermittent flow of oil. In such an installation, the gas pipe 76 and discharge pipe 16 are provided with branches (not shown) leading to the corresponding connections on the duplicate pumping mechanism, and suitable provision is made for venting the used operating gas into the chamber 84. By redesigning the mechanism shown in Fig. 4, it can be fitted into a semicircular portion of the tubing section 68, and the duplicate mechanism installed in the other semicircular portion thereof; or, by arranging properly for the connections to the operating gas pipe 76, discharge pipe 16, and gas vent chamber 84, the duplicate pumping mechanism can be installed vertically and immediately below the mechanism shown in Fig. 4.

In any of these cases, the valves of the duplicate mechanism corresponding to the valves 28, 30, and 31 will be operated by application and release of gas pressure thereto by means of a pipe 173 (see Fig. 8) leading from a port 174 (see Figs. 5 and 8) to the bore corresponding to the bore 107 in the mechanism shown in Fig. 4. It will be apparent that the valves of the duplicate mechanism will be operated in chronologically staggered fashion with respect to the valves of the mechanism shown in Fig. 4, and that while the pumping chamber of one mechanism is filling with oil, that of the other will be discharging, and vice versa, providing a continuous flow of oil through the discharge pipe.

When such a duplicate pumping mechanism is not provided, the port 174 is closed with a plug 175.

In the drawings and description, one embodiment of this invention has been set forth and described. Other embodiments will be apparent to those skilled in the art. I therefore do not limit myself to the particular embodiment herein shown. The invention is applicable to the pumping of liquids against any pressure head, as well as against the gravity head of wells. It is also applicable to the pumping of fluids as well as liquids. It will also be apparent that the principles of this invention can be used to lift the liquid to be pumped in several stages, the pumping mechanism shown and described herein being duplicated at one or more higher levels and installed to receive the liquid from the next lower pumping mechanism and lift it to the next higher pumping mechanism.

I claim as my invention:

1. In an apparatus for pumping liquids from wells: a submerged pumping chamber in the well communicating with the liquid in the well; a first conduit for discharging liquid and connecting said pumping chamber with the well surface; a first check valve between the liquid in the well and the pumping chamber adapted to open inwardly of said chamber; a second check valve adapted to open outwardly from said chamber into said liquid conduit; a source of pumping fluid under pressure; a second conduit connecting said source with said pumping chamber; an outlet for said pumping fluid from said pumping chamber; inlet and outlet valves controlling the flow of pumping fluid from said source to said chamber and from said chamber into said out-

let; means operated by fluid under pressure for mechanically opening said inlet valve and concurrently closing said outlet valve; an energy-storing retrieving means for mechanically closing said inlet valve and opening said outlet valve; a fluid operated means for closing said first check valve; a third conduit conducting fluid under pressure to said inlet and outlet valve operating means, and to said check valve closing means for the concurrent actuation of said inlet and outlet valve operating means and said check valve closing means; and means for intermittently interrupting the supply of fluid under pressure in said third conduit.

2. In an apparatus for pumping liquids from wells: a submerged pumping chamber in the well communicating with the liquid in the well; a first conduit for discharging liquid and connecting said pumping chamber with the well surface; a first check valve between the liquid in the well and the pumping chamber adapted to open inwardly of said chamber; a second check valve adapted to open outwardly from said chamber into said liquid conduit; a source of pumping fluid under pressure; a second conduit connecting said source with said pumping chamber; an outlet for said pumping fluid from said pumping chamber; inlet and outlet valves controlling the flow of pumping fluid from said source to said chamber and from said chamber into said outlet; means operated by fluid under pressure for mechanically opening said inlet valve and concurrently closing said outlet valve; an energy-storing retrieving means for mechanically closing said inlet valve and opening said outlet valve; an energy-storing retrieving means for mechanically opening said first check valve; a fluid operated means for mechanically closing said first check valve; a third conduit conducting fluid under pressure to said inlet and outlet valve operating means, and to said check valve closing means for the concurrent actuation of said inlet and outlet valve operating means and said check valve closing means; and means for intermittently interrupting the supply of fluid under pressure in said third conduit.

3. In an apparatus for pumping liquids from wells: a submerged pumping chamber in the well communicating with the liquid in the well; a first conduit for discharging liquid and connecting said pumping chamber with the well surface; a first check valve between the liquid in the well and the pumping chamber adapted to open inwardly of said chamber; a second check valve adapted to open outwardly from said chamber into said liquid conduit; a source of pumping fluid under pressure; a second conduit connecting said source with said pumping chamber; an outlet for said pumping fluid from said pumping chamber; inlet and outlet valves controlling the flow of pumping fluid from said source to said chamber and from said chamber into said outlet; means operated by fluid under pressure for mechanically opening said inlet valve and concurrently closing said outlet valve; an energy-storing retrieving means for mechanically closing said inlet valve and opening said outlet valve; an energy-storing retrieving means for mechanically opening said first check valve; a fluid operated means for mechanically closing said first check valve; a third conduit conducting fluid under pressure to said inlet and outlet valve operating means, and to said check valve closing means for the concurrent actuation of said inlet and outlet valve operating means and said check

valve closing means; and means for intermittently interrupting the supply of fluid under pressure in said third conduit, said means being chronometrically operated in a completely self-controlled manner and actuated by power continuously supplied at a substantially constant rate.

4. In an apparatus for pumping liquid from a well: a well casing within the well, closed at its lower end and extending above the surface of the liquid in the well, and provided with an aperture adjacent its lower end communicating with the liquid in the well; a first valve controlling the flow of liquid in said aperture; a plug in said 10 casing forming with the casing below said plug a pumping chamber and having four vertical ducts extending therethrough; a source of fluid under pressure at the surface of the well; a first conduit connecting said source with the first of 15 said ducts; a second conduit connecting said first conduit with the second of said ducts; a third liquid discharge conduit extending from the third of said ducts to the surface of the well; valves in the first and fourth of said ducts; 20 mechanism for suitably operating said valves to alternately apply and remove fluid pressure to and from liquid in said chamber; fluid pressure operated means mounted in said chamber for operating said mechanism; a fourth conduit connecting said second duct with said fluid pressure operated means; a fifth conduit extending from the lower end of said third duct downwardly within said chamber; an upwardly opening check 25 valve in the lower end of said fifth conduit; and 30 chronometric mechanism interposed in said second conduit adapted to intermittently interrupt the flow of fluid under pressure in said second conduit, said mechanism being adapted to be operated by the fluid under pressure in said second conduit.

5. In an apparatus for pumping liquid from a well: a well casing within the well, closed at its lower end and extending above the surface of the liquid in the well, and provided with an aperture adjacent its lower end communicating with the liquid in the well; a first valve controlling the flow of liquid in said aperture; a plug in said 45 casing forming with the casing below said plug a pumping chamber, and having four vertical ducts extending therethrough; a source of fluid under pressure at the surface of the well; a first conduit connecting said source with the first of said ducts; a second conduit connecting said first conduit with the second of said ducts; a third liquid discharge conduit extending from the third of said ducts to the surface of the well; valves in the first and fourth of said ducts; 50 mechanism for suitably operating said valves to alternately apply and remove fluid pressure to and from liquid in said chamber; fluid pressure operated means mounted in said chamber for operating said mechanism; a fourth conduit connecting said second duct with said fluid pressure operated means; a fifth conduit extending from the lower end of said third duct downwardly within said chamber; an upwardly opening check 55 valve in the lower end of said fifth conduit; chronometric mechanism interposed in said second conduit adapted to intermittently interrupt the flow of fluid under pressure in said second conduit, said mechanism being adapted to be operated by the fluid under pressure in said second conduit; means actuated by fluid under pressure for operating said first valve; and a sixth 60

conduit connecting said fourth conduit with said means for operating said first valve.

6. In an apparatus for pumping liquid from wells: a submerged liquid pumping chamber having a liquid intake port in its bottom wall communicating with the liquid in the well; a valve controlling the flow of liquid through said port; a liquid discharge conduit connecting said pumping chamber with the surface of the well; an upwardly opening check valve in said discharge conduit; intake and outlet fluid ports in the upper portion of said chamber; a valve in each of said ports; an upwardly extending bleeder conduit connected to said outlet fluid port; an upwardly extending first supply conduit connected to said intake fluid port; means for continuously supplying fluid under pressure in said first supply conduit to said fluid inlet port so as to tend to close said fluid inlet port valve; means adapted by a movement in one direction to open said fluid inlet port valve against the action of the fluid pressure in said first supply conduit and simultaneously close the fluid outlet port valve, and by a movement in the other direction to simultaneously reversely operate the valves; a pneumatic means for operating said valve operating means in said one direction; a mechanical energy-storing retrieving means for actuating said valve operating means in said other direction responsive to the termination of the operation of said pneumatic means; a second supply conduit connecting said first supply conduit with said pneumatic means; and means for intermittently interrupting the supply of fluid under pressure in said second supply conduit.

7. An apparatus as set forth in claim 6, and comprising in addition: completely self-controlled chronometric means for operating said interrupting means substantially unaffected by cyclic or other variations in the hydrostatic conditions of the pumped liquid.

8. In an apparatus for pumping liquid from wells: a submerged liquid pumping chamber having a liquid intake port in its bottom wall communicating with the liquid in the well; a valve controlling the flow of liquid through said port; a first pneumatic means for closing said valve; a mechanical energy-storing retrieving means for opening said valve responsive to the termination of the operation of said first pneumatic means; a liquid discharge conduit connecting said pumping chamber with the surface of the well; an upwardly opening check valve in said discharge conduit; intake and outlet fluid ports in the upper portion of said chamber; a valve in each of said ports; an upwardly extending bleeder conduit connected to said outlet fluid port; an upwardly extending first supply conduit connected to said intake fluid port; means for continuously supplying fluid under pressure in said first supply conduit to said fluid inlet port so as to tend to close said fluid inlet port valve; means adapted by a movement in one direction to open said fluid inlet port valve against the action of the fluid pressure in said first supply conduit and simultaneously close the fluid outlet port valve and by a movement in the other direction to simultaneously reversely operate the valves; a second pneumatic means for operating said valve operating means in said one direction; a second mechanical energy-storing retrieving means for operating said valve operating means in said other direction responsive to the termination of the operation of said second pneumatic means; a second supply conduit connecting said

first supply conduit with said first pneumatic means and with said second pneumatic means; and means for intermittently interrupting the supply of fluid under pressure in said second supply conduit.

9. An apparatus as set forth in claim 8 and comprising in addition: completely self-controlled chronometric means for operating said interrupting means substantially unaffected by cyclic or other variations in the hydrostatic conditions of the pumped liquid.

10. In a well having a well bore of substantially uniform diameter, the combination of: a tubing of sufficient diameter to be inserted in said well; walls forming a pumping chamber carried by said tubing and adapted to be submerged inside said well in the liquid in said well when said tubing carrying said chamber is lowered into said well; a liquid inlet valve so situated as to close a liquid inlet passage through which liquid may flow from said well into said chamber, said liquid inlet valve being so placed that it tends to open whenever liquid tends to flow from the well into the chamber and tends to close whenever liquid tends to flow from said chamber back into the well; a gas inlet valve so situated that it can close a gas passage through which gas can be admitted to said chamber from a source of gas supply; a relief valve so situated that it can close a relief passage through which gas may flow from said gas chamber to the space outside said tubing above the fluid in the well; a check valve so placed that it can close a liquid delivery passage through which liquid may flow from said chamber to a point above the surface of the ground, said check valve being so constructed that it automatically closes to prevent liquid from flowing from said delivery passage to said chamber and automatically opens to allow liquid to pass from said chamber to said delivery passage; a fluid actuated valve means for operating said gas inlet valve; a fluid actuated valve means for actuating said relief valve; a pilot valve so formed as to supply fluid under pressure to actuate all of said fluid actuated valve means and cause said gas inlet valve and said relief valve to operate in the proper sequence; a fluid actuated pilot valve operating means for operating said pilot valve; and chronometric means for controlling the application of fluid pressure to said fluid actuated pilot valve means and thus controlling the time used in performing each step of the operating cycle.

11. In a well having a well bore of substantially uniform diameter, the combination of: a tubing of sufficient diameter to be inserted in said well; walls forming a pumping chamber carried by said tubing and adapted to be submerged inside said well in the liquid in said well when said tubing carrying said chamber is lowered into said well; a liquid inlet valve so situated as to close a liquid inlet passage through which liquid may flow from said well into said chamber, said liquid inlet valve being so placed that it tends to open whenever liquid tends to flow from the well into the chamber and tends to close whenever liquid tends to flow from said chamber back into the well; fluid actuated valve means for positively causing said fluid inlet valve to open and close; a gas inlet valve so situated that it can close a gas passage through which gas can be admitted to said chamber from a source of gas supply; a relief valve so situated that it

can close a relief passage through which gas may flow from said gas chamber to the space outside said tubing above the fluid in the well; a check valve so placed that it can close a liquid delivery passage through which liquid may flow from said chamber to a point above the surface of the ground, said check valve being so constructed that it automatically closes to prevent liquid from flowing from said delivery passage to said chamber and automatically opens to allow liquid to pass from said chamber to said delivery passage; a fluid actuated valve means for operating said gas inlet valve; a fluid ac-

5 tuated valve means for actuating said relief valve; a pilot valve so formed as to supply fluid under pressure to actuate all of said fluid actuated valve means and cause said fluid inlet valve, said gas inlet valve, and said relief valve to operate in the proper sequence; a fluid actuated pilot valve operating means for operating said pilot valve; and chronometric means for controlling the application of fluid pressure to said fluid actuated pilot valve means and thus controlling the time used in performing each step of the operating cycle.

ROBERT T. KNAPP.

CERTIFICATE OF CORRECTION.

Patent No. 2,284,908.

June 2, 1942.

ROBERT T. KNAPP.

It is hereby certified that error appears in the printed specification of the above numbered patent requiring correction as follows: Page 3, first column, line 26, after "is" insert --generated by the--; and that the said Letters Patent should be read with this correction therein that the same may conform to the record of the case in the Patent Office.

Signed and sealed this 28th day of July, A. D. 1942.
